UNITED STATES PATENT OFFICE.

JAMES PASS AND ALBERT P. SEYMOUR, OF SYRACUSE, NEW YORK.

DESIGN FOR A SOCKET FOR INCANDESCENT LIGHTS.

SPECIFICATION forming part of Design No. 26,002, dated September 8, 1896.

Application filed February 14, 1896. Serial No. 579,318. Term of patent 14 years.

To all whom it may concern:

Be it known that we, JAMES PASS and ALBERT P. SEYMOUR, citizens of the United States, residing at Syracuse, in the county of Onondaga and State of New York, have invented and produced a new and original Design for Sockets for Incandescent Electric Lamps, of which the following is a specification, reference being had to the accompanying drawings, showing a part thereof.

Figure I is an elevation of a socket for incandescent electric lamps, showing our design. Fig. II is a top plan view of the same.

The feature of our design for a socket is the marginal configuration thereof, as better shown in Fig. I. From its smallest diameter at 1 the socket gradually increases in size with a slightly concave curved edge 2, which terminates in the flattened circumferential band 3. Near its lower edge, as here shown, the socket is provided with another flattened cir-

cumferential band 4, between which and the band 3 is the depressed portion 5. The upper portion 6 of the socket, as here shown, commonly called the "base," is provided with a projecting edge 7, which is slightly flattened to harmonize with the bands 3 and 4. The top of the base is preferably in the form of a flattened dome 8.

What we claim is—

The design for a socket, substantially as herein shown and described.

In witness whereof we have hereunto set our hands, in the presence of two attesting witnesses, at Syracuse, in the county of Onondaga, in the State of New York, this 1st day of February, 1896.

JAMES PASS.

ALBERT P. SEYMOUR.
